US00D639260S

(12) **United States Design Patent**
Carroll

(10) **Patent No.:** **US D639,260 S**
(45) **Date of Patent:** **** Jun. 7, 2011**

(54) **HAND-HELD MOBILE COMMUNICATION DEVICE**

(75) Inventor: **David W. Carroll**, Grantsburg, WI (US)

(73) Assignee: **JLT Group, Inc.**, ST. Paul, MN (US)

(**) Term: **14 Years**

(21) Appl. No.: **29/360,541**

(22) Filed: **Apr. 27, 2010**

(51) **LOC (9) Cl.** **14-03**

(52) **U.S. Cl.** **D14/138 G**; D14/341
